(57) **CLAIM**

The ornamental design for a wearable pet reservoir, as shown and described.

DESCRIPTION

FIG. 1 is a bottom perspective view of the wearable pet reservoir in accordance with my new design invention.

FIG. 2 is a front elevation view of the wearable pet reservoir of FIG. 1.

FIG. 3 is top plan view of the wearable pet reservoir of FIG. 1.

FIG. 4 is a bottom plan view of the wearable pet reservoir of FIG. 1.

FIG. 5 is a side elevation view of the wearable pet reservoir of FIG. 1; and,

FIG. 6 is a rear elevation view of the wearable pet reservoir of FIG. 1.

The portions of the drawings shown in broken line are for illustrative purposes only and form no part of the claimed design.
